CLAIM

The ornamental design for a horticulture lighting controller chassis, as shown and described.

DESCRIPTION

FIG. 1 is an exploded perspective view of a horticulture lighting controller chassis, as viewed from the front, showing our new design.

FIG. 2 is a perspective view of the rear component of the horticulture lighting controller chassis shown in FIG. 1, as viewed from the front;

FIG. 3 is a right side view of the rear component shown in FIG. 2;

FIG. 4 is a left side view of the rear component shown in FIG. 2;

FIG. 5 is a top elevation view of the rear component shown in FIG. 2;
FIG. 6 is a bottom elevation view of the rear component shown in FIG. 2;
FIG. 7 is a front plan view of the rear component shown in FIG. 2;
FIG. 8 is a rear plan view of the rear component shown in FIG. 2;
FIG. 9 is a perspective view of the front component of the horticulture lighting controller chassis shown in FIG. 1, as viewed from the front;
FIG. 10 is a right side view of the front component shown in FIG. 9;
FIG. 11 is a left side view of the front component shown in FIG. 9;
FIG. 12 is a top elevation view of the front component shown in FIG. 9;
FIG. 13 is a bottom elevation view of the front component shown in FIG. 9;
FIG. 14 is a front plan view of the front component shown in FIG. 9;
FIG. 15 is a rear plan view of the front component shown in FIG. 9;

FIG. 16 is a perspective view of the top component of the horticulture lighting controller chassis shown in FIG. 1, as viewed from the front;
FIG. 17 is a right side view of the top component shown in FIG. 16;
FIG. 18 is a left side view of the top component shown in FIG. 16;
FIG. 19 is a top elevation view of the top component shown in FIG. 16;
FIG. 20 is a bottom elevation view of the top component shown in FIG. 16;
FIG. 21 is a front plan view of the top component shown in FIG. 16; and,
FIG. 22 is a rear plan view of the top component shown in FIG. 16.
The horticulture lighting controller chassis comprising a kit of three separate components, a front component shown in FIGS. 9-15, a top component shown in FIGS. 16-22, and rear or backplane component shown in FIGS. 2-8.
The broken-line disclosure shown in the views is understood to represent portions of the article in which the claimed design is embodied, but which form no part of the claimed design.
